COSMETIC JAR

Harry P. Ansehl, University City, Mo.

Application October 8, 1951, Serial No. 16,877

Term of patent 14 years

(Cl. D58—25)

To all whom it may concern:

Be it known that I, Harry P. Ansehl, a citizen of the United States, residing at University City, county of St. Louis, State of Missouri, have invented a new, original, and ornamental Design for a Cosmetic Jar, of which the following is a specification, reference being made to the accompanying drawing, forming a part thereof, in which—

I claim:

The ornamental design for a cosmetic jar, substantially as shown.

HARRY P. ANSEHL.
